UNITED STATES PATENT OFFICE.

ONNIE M. KUSISTO, OF LEEDS, NEW YORK.

ATTACHMENT FOR PLIERS.

1,369,676.

Specification of Letters Patent. Patented Feb. 22, 1921.

Application filed May 12, 1919. Serial No. 296,423.

To all whom it may concern:

Be it known that I, ONNIE M. KUSISTO, a citizen of the United States, residing at Leeds, in the county of Greene and State of New York, have invented new and useful Improvements in Attachments for Pliers, of which the following is a specification.

The object of the invention is to provide a device for use in conjunction with pliers to adapt the latter particularly to the ready removal of the binding wires employed to bind bales of hay, the device being designed to remove the binding wires without cutting them, so that they may be reëmployed for the binding of new bales.

A further object of the invention is to provide an attachment for pliers which is simple in construction, durable and effective in operation and inexpensive to manufacture.

Other and further objects appear in the following description wherein the invention is set forth in detail.

To the exact construction in which it is shown and described, the invention is not to be restricted. The right is reserved to make such changes or alterations as the actual reduction to practice may suggest, in so far as such changes or alterations are compatible in spirit with the annexed claims.

In the accompanying drawings:

Figure 1 is a perspective view of the invention showing the latter in its initial position for gripping the two ends of a binding wire of a bale of hay for the removal of said binding wire.

Fig. 2 is a perspective view showing the manner in which the ends of the binding wire are bent to effect their loosening.

Fig. 3 is a side elevational view of the jaws of the plier and the attachment.

Fig. 4 is a plan view of the attachment.

Fig. 5, is a view similar to Fig. 3 to show the attachment shifted to inoperative position.

Referring to the drawings, there is shown a pair of pliers having the usual jaws 1 and the handles 2, these two jaws being pivotally connected together as is usual, by means of the pivot stud 3. The stud 3 besides serving to connect the two elements of the pliers together, also serves to secure the improved attachment to the pliers and this attachment comprises a block 4 formed with two space stationary jaws 5 which are spaced from each other and which have their facing edges parallel as clearly indicated in

Fig. 4. The block is formed with an eye 6 through which the pivot stud passes and the block may be swung around to bring its jaws underneath the jaws of the pliers or turned in the opposite directions to bring its jaws underneath the handle portions of the pliers, when the pliers may be used for ordinary purposes.

For use of the device in removing the binding wires of a bale of hay, the block 4 is swung around to the position indicated in Fig. 3 and thus the jaws 5 lie substantially below the plier jaws. The two jaws 5 of the block are then made to straddle the binding wire below the eye 7 as indicated in Figs. 1 and 2, whereupon the jaws of the pliers are engaged with the outer strand of the wire loop forming the hook 8. The block 75 cannot rise higher than the eye 7 for the wire adjacent the eye is seated in the crotch between the two legs of the block and the latter is, therefore, fulcrumed at this point and with the two plier jaws gripping the 80 outer strand of the latter forming the hook 8, the pliers may be forced downwardly at the handle ends with the result that the movement takes place with the crotch between the two jaws as a pivot and the loop comprising the hook 8 is distorted by the pull exerted by the pliers as indicated in Fig. 2 and may thus be easily disengaged from the eye when the two ends of the binding wire are under tension as indicated in Fig. 2. 90

The invention having been described, what is claimed as new and useful is:

1. The combination with a pair of pliers, of a block attached to the pliers and carried beside the jaws thereof, the block being 95 formed to provide two spaced stationary jaws for the useful purpose specified.

2. The combination with a pair of pliers, of a block attached to the pliers, the block being provided with a pair of spaced stationary jaws, its means of attachment to the pliers permitting its jaws to be disposed adjacent the plier jaws or shifted to a position where they are remote from the plier jaws.

3. The combination with a pair of pliers, of a pivot stud connecting the plier elements together, and a block pivotally carried on said stud and formed with a pair of spaced stationary jaws for the useful purpose 110 specified.

In testimony whereof I affix my signature.

ONNIE M. KUSISTO.
